UNITED STATES PATENT OFFICE.

EDWIN I. NOTTINGHAM, OF WASHINGTON, DISTRICT OF COLUMBIA, ASSIGNOR TO THE
YALE & TOWNE MANUFACTURING COMPANY, OF STAMFORD, CONNECTICUT.

FACING-RING STRUCTURE FOR LOCKS.

Application filed December 29, 1922. Serial No. 609,636.

To all whom it may concern:

Be it known that I, EDWIN I. NOTTINGHAM, a citizen of the United States, and a resident of Washington, District of Columbia, have invented certain new and useful Improvements in Facing-Ring Structures for Locks; and I do hereby declare the following to be a full, clear, and exact description of the invention, such as will enable others skilled in the art to which it appertains to make and use the same.

This invention relates to improvements in facing or rose ring structures for cylinder locks,—one object of the invention being to provide such a structure which shall include a substantial armor body portion and a scalp member of thin metal, and in which the scalp member shall be utilized to provide spring means integral therewith for cooperation with the flanged head of a cylinder lock to insure a close fit of said head relatively to the facing ring should it become necessary to turn the cylinder in such manner as to cause the plug of the lock to be located in the lower portion of the cylinder when the lock is applied to a door.

With this and other objects in view, the invention consists in certain novel features of construction and combinations of parts as hereinafter set forth and pointed out in the claims.

In the accompanying drawings,—

Figure 1 is a sectional view of a facing ring structure showing an embodiment of my improvements.

Figure 2 is a front view with the lock cylinder omitted.

Figure 3 is a face view illustrating a modification, and

Figure 4 is a sectional view (with a portion of the lock in elevation) of the structure shown in Figure 3.

In the embodiment of the invention shown in Figures 1 and 2, the body portion of the device is represented at 1 and may consist of a ring or annulus of steel or hardened metal,—said ring or annulus being formed with an interior annular recess 2.

The body portion 1 of the ring is covered by a scalp 3 of thin spring metal. The rear portion of the scalp may be bent over the peripheral edge of the body ring 1 and the forward portion of said scalp is made with an annular inwardly projecting por-

tion 4 which may constitute a lining for a part of the wall of the recess 2 in the ring 1. The inwardly projecting portion 4, of the scalp may be slit radially at intervals to provide an annular series of integral spring fingers 5 which are bent inwardly and forwardly within the recess 2 of the ring 1 in a manner to be engaged by the flanged head 6 of a lock cylinder 7 and thus afford for said cylinder a yielding connection with the ring and insure a proper connection between these parts even though necessity may arise to turn the cylinder in properly positioning the lock plug.

In the embodiment of the invention shown in Figures 3 and 4, the inwardly extending annular portion 4 of the scalp is continued to the annular shoulder 8 formed by the recess 2 in ring 1, and the inner end of the scalp portion 4 is made to project inwardly over said shoulder to form an annular flange as indicated at 9. The inwardly projecting flange 9 is split in a manner to form a series of concentric spring fingers 10 which are made to project forwardly in a manner to be engaged by the flanged head 6 of the lock cylinder 7 as shown in Figure 4.

Having fully described my invention what I claim as new and desire to secure by Letters Patent, is:

1. The combination with a facing ring, of an annular sheet metal portion embracing the same and having an inwardly projecting split annular member forming a plurality of spring fingers.

2. The combination in a facing ring structure, of a body ring, a scalp for said body ring, and yielding means for the head of a cylinder lock, said yielding means constituting an integral part of the scalp.

3. The combination in a facing ring structure, of a body ring and a scalp therefor, said scalp having integral spring fingers positioned within the body ring to be engaged by the flanged head of a cylinder lock.

4. The combination in a facing ring structure, of a body ring having an interior annular recess, a covering scalp and spring means for the flanged head of a cylinder lock, integral with said scalp and located in said annular recess.

5. The combination in a facing ring struc-

ture, of a body ring and a covering scalp having an integral inwardly projecting portion entering the body ring and split forming a series of spring fingers integral with the scalp.

6. The combination in a facing ring structure, of a body ring having an interior annular recess, and a scalp having an integral portion entering the ring and having an 10 annular series of spring fingers located

within said recess positioned to receive the flanged head of a lock cylinder.

In testimony whereof, I have signed this specification in the presence of two subscribing witnesses.

EDWIN I. NOTTINGHAM.
